Inventor:

W.M. Duncan

by Cook & McCleary Pitts

UNITED STATES PATENT OFFICE.

WILLIAM M. DUNCAN, OF ALTON, ILLINOIS.

CHAIN GRATE.

Application filed August 18, 1921. Serial No. 493,198.

To all whom it may concern:

Be it known that I, WILLIAM M. DUNCAN, a citizen of the United States of America, and a resident of Alton, in the county of 5 Madison and State of Illinois, have invented certain new and useful Improvements in Chain Grates, of which the following is a full, clear, and exact description, reference being had to the accompanying drawings, 10 forming a part of this specification.

This invention relates to improvements in chain grates, the main object being to produce a chain grate adapted to receive very fine fuel without undue loss of the fuel at 15 the draft passageways in the grate. In a chain grate, the grate links should be separated from each other to provide passageways for the admission of draft to the fuel. The problem of admitting adequate draft 20 and at the same time preventing free escape of fine fuel, is a difficult one that has never been entirely solved, and my object is to produce a chain grate from which these results can be most effectively obtained.

25 In the preferred form of the invention, the flexible chain grate is provided with pivotally connected grate links having longitudinal baffle ribs which obstruct the fuel tending to pass through the grate. These 30 baffle ribs are so formed that the draft can pass freely to the fuel, and they do not in any way interfere with the pivotal movements of the links. Furthermore, the baffles are so arranged that any fine particles of 35 fuel entering between the links will be discharged when the links turn on their pivots, so the links are repeatedly cleaned while the grate is in motion.

40 A further object is to prevent free escape of ashes through the grate structures, and this is of course accomplished by the means for preventing free escape of fine particles of fuel.

45 A further object is to provide an effective means for preventing the draft from flowing lengthwise of the grate at points between the links.

With the foregoing and other objects in view, the invention comprises the novel construction, combination and arrangement of parts hereinafter more specifically described and illustrated in the accompanying drawings wherein is shown the preferred embodiment of the invention. However, it is 55 to be understood that the invention comprehends changes, variations and modifications

which come within the scope of the claims hereunto appended.

Fig. I is a top view, partly in section, 60 illustrating several rows of grate links embodying the features of this invention, the section being in the plane of the pivot rods.

Fig. II is a side elevation of the structure shown in Fig. I, some of the links being shown by dot and dash lines to illustrate the 65 pivotal motion of the links.

Fig. III is a vertical section taken approximately on the line III—III in Fig. II.

Fig. IV is a vertical section taken approximately on the line IV—IV in Fig. II, some 70 of the parts distant from said line being omitted.

Fig. V is a perspective view showing one side of the new grate link.

Fig. VI is a perspective view showing the 75 other side of the link.

The links shown by Figs. I, II, III and IV can be made exactly alike, and one of these links is shown by Figs. V and VI. I will describe one of the links and then 80 point out the manner in which the several links cooperate with each other.

Each link is provided with a longitudinal baffle rib A extending approximately 85 from end to end of the link and projecting from the top margin of one of the side faces of the link. Each link also has a lower longitudinal baffle rib B extending from end to end of the link and projecting from the other side face thereof. Fig. IV shows that 90 the rib B at one side of the link is lower than the rib A at the other side. Transverse grooves 1 are formed in the top face of the link, as shown most clearly by Figs. V and VI, and these grooves are continued 95 down the side faces of the baffle rib A. The lower portion of each link is provided with a pair of pivot receiving openings 2 (Fig. V) formed near the ends of the link. The bottom face of the rib A is provided with 100 curved portions 3 coaxial with the respective openings 2, and the baffle rib B has curved top faces 4 coaxial with these openings. 5 designates pivot rods passing through the openings 2, so as to pivotally 105 connect the several links.

When the links are assembled, as shown by Fig. IV, the baffle ribs A overlap the ribs B, and the bottom face of each rib A is separated from the top face of a lower rib B. 110 Each rib B is separated from the side face of the next adjacent link, so the draft can

pass freely between the links and escape to the fuel supported on the top faces of the links.

Figs. I and II show that the links are arranged in straight rows which are pivotally connected by the rods 5 to provide a flexible chain grate. For reasons well understood in this art, the links are movable about the axes of the pivot rods 5, as suggested by the dot and dash lines in Fig. II, and since the lapped faces of the baffle ribs A and B are coaxial with the respective pivots, it will be understood that these ribs do not in any way interfere with the pivotal movements of the links. The baffles A in each row of links overlap the baffles B in the next adjacent row so as to obstruct fine particles of fuel, or ashes, tending to pass between the sides of the links.

In the grate structure I have shown, the links of adjacent rows are staggered relative to each other, as shown most clearly by Fig. I, so that the links in an interposed row are not in alinement with the links at opposite sides thereof. In other words, the longitudinal baffle rib A of each link overlaps the baffle ribs B on two of the links in the next adjacent row, but the ribs are so formed that each link can turn freely on its two pivot rods 5.

I will now refer to vertically disposed baffle ribs which impede air currents tending to flow longitudinally of the grate. As shown by Figs. V and VI, each grate link is provided on one of its sides with a vertical baffle rib 8 extending from the longitudinal rib A to the lower edge of the link. The opposite side of each link is provided with a vertical baffle rib 9 extending from the rib B to the lower edge of the link. When the links are assembled, one of the vertical ribs 8 lies adjacent to one of the ribs 9, as shown by Figs. I and III, and these adjacent ribs lie between the ends of two links. They prevent the fuel from dropping between the adjacent ends of the links, and they impede air currents tending to flow longitudinally of the grate. Each rib 8 is provided with a lateral extension 8' (Figs. III and V) which extends into a recess at the top of a rib 9. Each rib 8 is thus extended to overlap a rib 9, and the overlapping portions lie immediately below the space between the ends of two links. The ribs 8 and 9 on any one of the links lie midway between the ends of the links, and these ribs are extended from the several rows of links, so that any two companion ribs 8 and 9 extend across an interposed row of the links at points directly below the adjacent ends of two links in the interposed row.

I claim:

1. A flexible chain grate comprising rows of pivotally connected grate links, each of

said links having on one of its sides an upper longitudinal baffle rib formed at its top margin and extending approximately from end to end of the link, each link also having on its opposite side a lower longitudinal baffle extending approximately from end to end of the link, the lower longitudinal baffles on the links in one row being overlapped by the upper longitudinal baffle ribs on the links in the next adjacent row, and said lower longitudinal baffles being separated from the overlapping upper longitudinal baffles to provide for the delivery of draft between the baffles. 70

2. A flexible chain grate comprising rows of pivotally connected grate links, each of said links having on one of its sides an upper longitudinal baffle rib formed at its top margin and extending approximately from end to end of the link, each link also having on its opposite side a lower longitudinal baffle extending approximately from end to end of the link, the lower longitudinal baffles on the link in one row being overlapped by the upper longitudinal baffle ribs on the links in the next adjacent row, each lower longitudinal baffle having a top face adjacent to but separated from the bottom face of an upper longitudinal baffle rib, and said faces having curved portions 90 approximately coaxial with the corresponding connecting pivots. 85

3. A grate link having an upper longitudinal baffle at the upper edge of one of its side faces, and a lower longitudinal baffle at the upper portion of its other side face. 100

4. A grate link having an upper longitudinal baffle at the upper edge of one of its side faces, and a lower longitudinal baffle at the upper portion of its other side face, said link also having pivot-receiving openings, and portions of said longitudinal baffles being approximately co-axial with the respective openings. 105

5. A grate link having an upper longitudinal baffle at the upper edge of one of its side faces, and a lower longitudinal baffle at the upper portion of its other side face, the lower portion of said link having pivot-receiving openings, said upper longitudinal baffle having bottom faces approximately co-axial with the respective openings, and said lower longitudinal baffle being provided with top faces approximately co-axial with the respective openings. 110

6. A chain grate comprising endless rows of grate links, the links of adjacent rows being staggered relative to each other so that the links in an interposed row are not in transverse alinement with the links at opposite sides thereof, the links in each of said rows being provided with transverse baffle ribs which extend between end portions of the links in an adjacent row, so 125 130

as to impede air currents tending to flow longitudinally of the grate, and the baffle ribs in one of said rows being overlapped by the baffle ribs in another of said rows.

5 7. A chain grate comprising endless rows of grate links, the links of adjacent rows being staggered relative to each other so that the links in an interposed row are not in transverse alinement with the links at opposite sides thereof, the links in each of said rows being provided with transverse baffle ribs which extend between end portions of the links in an adjacent row, so as to impede air currents tending to flow 10 longitudinally of the grate, the upper end of each of said baffles being provided with a lateral extension overlapping another of said baffles.

20 8. A chain grate comprising endless rows of grate links, the links of adjacent rows being staggered relative to each other so that the links in an interposed row are not in transverse alinement with the links at opposite sides thereof, the links in each of said rows being provided with transverse baffle ribs which extend between end portions of the links in an adjacent row, so as to impede air currents tending to flow 25 longitudinally of the grate, the upper end of each of said baffles being provided with a lateral extension overlapping another of said baffles, and the overlapping portions of the baffles being located between the adjacent ends of two of said links.

30 35 9. A grate link having oppositely disposed baffle ribs on its side faces, said baffle ribs ex-

tending from the lower margin of the link to the upper portion thereof, one of said ribs having a lateral extension and the other rib having a recess formed opposite to said 40 lateral extension, said extension being adapted to extend into a recess in a rib of an adjacent grate link and said recess being adapted to receive an extension on a rib of an adjacent grate link when the grate 45 link forms a part of an assembled grate.

10. A flexible chain grate comprising rows of pivotally connected grate links, the links of one row being provided with longitudinal baffle ribs overlapping portions of the 50 links in the next adjacent row, each of said links also having transverse baffles overlapping portions of the links in another row.

11. A flexible chain grate comprising rows of pivotally connected grate links, each of the links in one of said rows being provided with a longitudinal baffle rib formed at its upper margin and extending approximately from end to end of the link, and each link in the next adjacent row being provided with a longitudinal baffle rib at its upper portion overlapped by two of the longitudinal ribs of the other row, so as to prevent free escape of fuel between the 55 links, each of said links also having a transverse baffle rib extending from its longitudinal baffle rib to the lower margin of the link.

In testimony that I claim the foregoing I hereunto affix my signature.

WILLIAM M. DUNCAN.
